WEB CONTROLLING MECHANISM

Harland Fankboner, Chicago, Ill.

Application October 30, 1931. Serial No. 572,026

7 Claims. (Cl. 242—75)

The present invention relates to web controlling means and more particularly to a novel and improved web tensioning mechanism for use with high speed rotary printing presses.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:

Figure 1 is a side elevation of a mechanism constituting the present preferred and illustrative embodiment of the invention; and

25 Figure 2 is a vertical section taken on the line 2—2 of Figure 1.

The present invention has for its object the provision of a web tensioning mechanism which will operate satisfactorily with uneven or out-of-round web rolls. Another object is the provision 30 of a web tensioning mechanism employing a plurality of friction members in engagement with the periphery of the web roll, and having means for maintaining equal the pressure between the friction members and the web roll. Still another 35 object is the provision of a tension mechanism in which the straps engaging the periphery of the web roll are so interconnected that movement of any one strap is transmitted to the others to equalize the pressure of all the straps against the 40 roll.

Referring now in detail to the present preferred and illustrative embodiment of the invention, the web roll 1, from which the web 2 is fed to the printing press, is rotatably supported by 45 means of web roll shaft 3 journalled in suitable bearings 4 formed in web roll supporting brackets 5 at either side of the web roll. Brackets 5 may be conveniently formed as an integral part of the side frames 6 of the printing press, although any other desired or suitable form of web roll supporting means may be employed.

50 For tensioning the web, there are provided a plurality of friction members yieldingly pressed into engagement with the periphery of the web roll across its width, said friction members serv-

ing to restrain the rotation of the web roll. As embodied, these friction members comprise flexible straps 7, attached at their upper ends to rollers 8 slidably keyed to a shaft 9, while their lower ends are attached in a manner later to be described. Means are provided for pressing the straps against the surface of the web roll with a substantially uniform, but variable, pressure, and for taking up slack in the straps as the web roll wears down. For this purpose, the shaft 9 is rotatably journalled in the lower ends of arms 10, rigidly attached to a shaft 11 journalled in the side frames 6. At one end shaft 11 is provided with a laterally projecting threaded arm 12 on which is mounted a correspondingly threaded weight 13, tending to rotate the arms 10 and their shaft 11. At one end, shaft 9 is provided with a pinion 14 meshing with a segmental rack 15 fixed to the inner side of one side frame 6, so that movement of arms 10 by weight 13 rotates the 70 shaft 9 and rollers 8 to take up the slack in the straps and maintain them in contact with the surface of the web roll. The normal tension of the web may be varied by movement of weight 13 on threaded arm 12, and as weight 13 is moved outwardly, the pressure between the belts 7 and the web roll is increased, thereby increasing the 75 tension on the web.

Means are provided for rendering the pressure of all the straps against the web roll equal at all 80 times, thereby preventing the exertion of excessive pressure between any belt and the web roll due to unevenness in the rolls. For this purpose, the lower end of each strap is provided with a pulley 17 attached thereto. Below the web roll, 85 and extending substantially parallel to its axis, is a transverse rod 18, rigidly supported in the side frames 6, and provided along its length with collars 19 and 20. Collars 20, near the ends 90 of the roll, are provided with eyes 21 and freely rotatable guiding pulleys 22 while the inner collars 19 are provided with pairs of spaced pulleys 22. A flexible cable 23 is attached at its ends to eyes 21, at either end of the web roll and is 95 looped over pulleys 17 between the guiding pulleys 22.

As collars 20 are slideable along the supporting rod 18 and rollers 8 are movable transversely with respect to the web, the strap 7 may be positioned as desired across the width of the web 105 roll. When properly positioned collars 20 are firmly secured in position by set screws 24.

In operation, the straps 7 are normally pressed into engagement with the surface of the web roll, and maintained in engagement therewith with 110

a constant but variable pressure, as the web roll wears down by means of weight 13 which rotates rollers 8 to take up the slack in the straps. When an uneven or out-of-round web roll is mounted in web feeding position, the high parts of the web roll tend to increase the tension on one or more of the straps, as the high part of the roll moves the straps out of their normal position. Any movement of one strap causes the corresponding loop in cable 23 to be enlarged shortening the remaining loops and thereby reducing the pressure between the first strap and the roll and transmitting a portion of this pressure to the remaining straps. This action prevents the building up of excessive pressure between any one strap and the web roll distributing the additional pressure over all of the straps so that only a slight and unobjectionable increase in pressure is created, preventing an abnormal and excessive increase in the tension of the web. Similarly, in case one of the straps stretches to a greater extent than the remainder the pressure of all remains equal and no individual adjustment of the straps is necessary as their pressure is always equalized.

The invention in its broader aspects is not limited to the specific mechanisms shown and described but departures may be made therefrom within the scope of the accompanying claims without departing from the principles of the invention and without sacrificing its chief advantages.

What I claim is:

1. Web controlling mechanism including in combination means for rotatably supporting a web roll, a plurality of friction straps pressed into engagement with the periphery of the web roll to tension the web drawn therefrom and means interconnecting said straps for equalizing their pressure against the roll.

2. Web controlling mechanism including in combination means for rotatably supporting a web roll, a plurality of friction straps engaging the periphery of the web roll, means for pressing the straps against the web roll with a uniform tension as the web roll wears down, and interconnecting means between the straps and a stationary support for equalizing the pressure between them.

3. Web controlling mechanism including in combination means for rotatably supporting a web roll, a plurality of friction members yieldingly pressed into engagement with the periphery

of the web roll and means interconnecting said members for equalizing their pressure against the roll.

4. Web controlling mechanism including in combination means for rotatably supporting a web roll, a plurality of friction straps pressed into engagement with the periphery of the web roll to tension the web drawn therefrom, a common support to which the straps are attached at one end, a transverse member extending across the width of the web roll, a cable attached to the member to provide loops adjacent the other end of each strap and means for movably connecting each strap to its corresponding loop.

5. Web controlling mechanism including in combination means for rotatably supporting a web roll, a plurality of friction straps pressed into engagement with the periphery of the web roll to tension the web drawn therefrom, a common support to which the straps are attached at one end, a transverse member extending across the width of the web roll, a cable having both its ends attached to said member, guides on said member between each pair of straps, and means for movably attaching the other end of each strap to the cable between the guides.

6. Web controlling mechanism including in combination means for rotatably supporting a web roll, a plurality of friction straps pressed into engagement with the periphery of the web roll to tension the web drawn therefrom, a common support to which the straps are attached at one end, a transverse member extending across the width of the web roll, a cable having both its ends attached to said member, guides on said member between each pair of straps, pulleys on the other end of each strap around which the cable is passed between said guides.

7. Web controlling mechanism including in combination means for rotatably supporting a web roll, a plurality of friction straps pressed into engagement with the periphery of the web roll to tension the web drawn therefrom, a common support to which the straps are attached at one end, a transverse member extending across the width of the web roll, a cable having both its ends attached to said members, guide pulleys on said member between each pair of straps, a pulley on the other end of each strap and around which the cable is passed between its adjacent guides.
